US00D523344S

(12) **United States Design Patent** (10) **Patent No.:** **US D523,344 S**
(45) **Date of Patent:** **** Jun. 20, 2006**

(54) **CONTAINER WITH CAP**

(75) Inventors: **Mary Toth**, Ann Arbor, MI (US);
Javier Verdura, Milford, CT (US);
Craig Pirie, Ontario (CA); **Daniel Peter Sterling**, Bridgeport, CT (US);
Erik Joseph Moses, New Haven, CT (US); **Peter Michaelian**, New York, NY (US); **Kristin Recchiuti**, North Wales, PA (US); **Leonard Wojnarowicz, Jr.**, Willow Grove, PA (US); **John Spano**, Bordentown, NJ (US); **Roger Rinker**, Hatfield, PA (US)

(73) Assignee: **McNeil-PPC, Inc.**, Skillman, NJ (US)

(**) Term: **14 Years**

(21) Appl. No.: **29/219,722**

(22) Filed: **Dec. 21, 2004**

(51) **LOC (8) CL. 09-01**

(52) **U.S. CL. D9/522; D9/529**

(58) **Field of Classification Search** D7/612-615,
D7/629; D9/516, 522-523, 529, 530, 542-543,

(57) **CLAIM**

The ornamental design for a container with cap, as shown and described.

DESCRIPTION

FIG. 1 is a perspective view of the container with cap of our new design as seen from the top, front, and left side;

FIG. 2 is a front elevational view thereof;

FIG. 3 is a right side elevational view thereof, the left side elevational view being a mirror image;

FIG. 4 is a rear elevational view thereof;

FIG. 5 is a top plan view thereof;

FIG. 6 is a bottom plan view thereof;

FIG. 7 is a perspective view of a second embodiment of the container with cap of our new design as seen from the top, front, and left side;

FIG. 8 is a front elevational view thereof;

FIG. 9 is a right side elevational view thereof, the left side elevational view being a mirror image;

FIG. 10 is a rear elevational view thereof;

FIG. 11 is a top plan view thereof;

FIG. 12 is a bottom plan view thereof;

FIG. 13 is a perspective view a third embodiment of the container with cap of our new design as seen from the top, front, and left side;

FIG. 14 is a front elevational view thereof;

FIG. 15 is a right side elevational view thereof, the left side elevational view being a mirror image;

FIG. 16 is a rear elevational view thereof;

FIG. 17 is a top plan view thereof;

FIG. 18 is a bottom plan view thereof;

FIG. 19 is a perspective view a fourth embodiment of the container with cap of our new design as seen from the top, front, and left side;

FIG. 20 is a front elevational view thereof;

FIG. 21 is a right side elevational view thereof, the left side elevational view being a mirror image;

FIG. 22 is a rear elevational view thereof;

FIG. 23 is a top plan view thereof; and,

FIG. 24 is a bottom plan view thereof.

The broken lines shown in the drawings are for environmental purposes only and form no part of the claimed design.
